(57) **CLAIM**

The ornamental design for a CSP LED strip light, as shown and described.

DESCRIPTION

FIG. 1 is a perspective view of a CSP LED strip light showing my new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of the portion labeled “8” in FIG. 1; and,

FIG. 9 is an enlarged view of the portion labeled “9” in FIG. 6.

In FIG. 1, FIG. 6, FIG. 8, and FIG. 9, a broken line frame defines the boundary of an enlarged view and forms no part of the claimed design.

1 Claim, 9 Drawing Sheets(56)
